UNITED STATES PATENT OFFICE.

JOHN LAWSON, OF CENTRAL FALLS, RHODE ISLAND.

CIRCULAR-KNITTING MACHINE.

1,192,328.

Specification of Letters Patent. Patented July 25, 1916.

Application filed May 31, 1912. Serial No. 700,569.

To all whom it may concern:

Be it known that I, JOHN LAWSON, a citizen of the United States, residing at Central Falls, in the county of Providence and State 5 of Rhode Island, have invented certain new and useful Improvements in Circular-Knitting Machines, of which the following is a specification.

My invention relates to automatic circular 10 knitting machines, and it consists in the novel construction and arrangement of parts, as hereinafter set forth.

In certain types of knitting-machines, the transferring of knitted "tops" to the needles 15 is frequently attended with breakage or injury to some of the sinkers and needles and also to the transfer-ring's grooved points. Such defects are largely due to the fact that while the latch-guard is raised the positioned 20 transfer-ring is adapted to temporarily revolve simultaneously with the cylinder and its guided sinkers and needles; the sinker-cam ring employed for moving the sinkers inward and outward at certain places 25 while the parts referred to are thus revolving being held against rotation, so that if, in the event any of said needles, sinker or "point" members happen to be slightly out of axial alinement or true the inner ends of 30 such sinkers, in moving inward from the extreme outward position, are liable to engage the adjacent grooved point or its needle, or both, resulting in material injury to the parts and possibly to the "top" itself.

The object I have in view is to provide 35 knitting-machines of the general type referred to with means such that the injury and loss formerly attending the transferring operation will be practically eliminated, 40 thereby materially increasing the efficiency of the machine. This result is accomplished by permitting the sinker-cam ring to revolve concurrently with the needle-cylinder, thereby temporarily preventing endwise movement 45 of the sinkers and rendering them, for the time being, relatively stationary with the points of the transfer-ring.

In the accompanying sheet of drawings, 50 Figure 1 represents a top plan view of the revolvable needle-cylinder, its relatively stationary cap or sinker-cam ring for normally causing the sinkers to move in an endwise or radial direction while they are at the same time revolving bodily with the needle-cylinder and its sinker-ring, some of the 55 parts being omitted; Fig. 2 is a side eleva-

tion, in reduced scale, of the upper portion of the needle-cylinder, the sinker-ring and its cam-ring, showing a transfer-ring positioned on the cylinder while they are being 60 rotated to elevate the needles into the respective quills or points, the latch-guard meanwhile being elevated; Fig. 3 is a partial transverse sectional view, enlarged scale, on lines 3—3 of Figs. 1 and 4; Fig. 4 is a 65 partial horizontal sectional view, taken substantially on line 4—4 of Fig. 3; and Fig. 5 is an inverted plan view, in reduced scale, showing portions of the sinker-cam ring.

It may be stated that only enough of the 70 parts of a revolvable needle-carrying cylinder knitting-machine are represented to show the position and relation of the transfer-ring thereto when the transfer operation is being effected.

75

A, in the drawings, indicates the revolvable needle-cylinder, or rather the upper portion of it, to which is secured a sinker-ring g, supporting a concentric cap or sinker-cam ring C; these members serve conjointly to 80 bodily rotate the sinkers and also to move them inward and outward at certain places during the normal knitting operation, in a well-known way. Now, in order to allow the ring C, normally held against complete 85 rotation, to revolve with the cylinder while the transference of the "top" to the empty needles is taking place, the transfer-ring B, having its quills or points b inserted through the respective loops or stitches of the "top", 90 is placed centrally upon the member C; the latch-guard being first elevated, as indicated in Fig. 2, the result being to move all the needles upward into the loop-carrying quills while the needle-cylinder is being tempo- 95 rarily manually rotated one or more turns, and so that upon removing the ring element B the "top" will be left positioned upon the needles to be then interknitted into the fabric, as usual.

100

The drawings represent a post e to which the shank a of the latch-guard D is pivoted at e¹. When the member D is dropped to the normal or horizontal position, the presence of its arm a, then interposed between the inwardly facing separated horizontal stops f, f, adjustably mounted in the uprights c¹ of the U-shaped bracket member c fixed to the top of said ring C, prevents the latter from revolving with the cylinder, although permitting it to vibrate slightly back and forth during reciprocatory knitting.

105

110

The stops *f* when adjusted are maintained in place by means of the set or clamp-screws *c*². When, however, the latch-guard is raised, such raising of the latch guard will move the arm *a* out of line with said stops, and so that the sinker-cam-ring *C* will then be free to rotate with the needle-cylinder, and by reason of the friction between the parts will rotate therewith, thereby preventing any inward movement of the sinkers and avoiding the danger of the inner ends of the sinkers being brought into contact with either the needles or the points of the transfer-ring.

In knitting-machines, in which the needle-cylinder rotates (and in normal action), the sinker-cam ring thereof is practically non-revolvble, except as just stated, the cam *d* at the same time causing the previously retracted sinkers to move inward at or near the point *d*¹, or where the needles receive the knitting-thread. Fig. 1 shows the relation of the parts in normal knitting. In transferring "tops" to the needles, however, the act of rotating the cylinder one or two revolutions in order to force the needles upward into the quills of the transfer-ring *B* positioned on the ring *C* also acts to impart independent movement to the sinkers (radially) while they are in engagement with the cam *d*, and as the head portions of the sinkers at said cam point are then wholly in front of the corresponding needles and quills, the nose part *o*² of the thus moving sinkers are liable to engage the needles or quills and cause breakage or serious injury to them, and necessitating replacement by new members. Fig. 4 indicates the direction of the inwardly extending sinkers *o* in normally moving in the narrow space formed between the adjacent sides of the quills; *o*¹ designates the heads over which stitches are cast into the web, and *o*² the nose or point. One of the latter, sprung laterally out of true, is shown at *o*^x. Obviously, a further inward movement of the sinker would result in more or less damage to the parts. By the present construction such inward movement of the sinkers is prevented and the liability of breakage or injury referred to is avoided.

In lieu of providing the ring *C* with outwardly projecting stop-carrying arms in continuous engagement with the post *e*, or some other suitable stationary member of the machine, I employ means secured to said ring constructed to move freely past the post *e* and latch-ring when the latter is elevated, substantially as shown in Fig. 2, and as before described. After the "top" has been threaded on the needles and the ring *B* removed, the cylinder is stopped, the bracket *c* of the cam-ring *C* then lying adjacent the post *e* carrying the latch-ring; the latter is then dropped to its normal limit, thereby placing its shank *a* between the two stops *f*—see Fig. 1. Upon restarting the machine to

produce normal rotary or plain knitting, the said element *C* will be held against rotation by one or the other of the stops *f*, according to the direction of the cylinder's movement. Of course, a degree of oscillation or play is permitted in order to insure a better intake of the thread into the needle's hooks at the thread-feeding point, as usual.

I claim:

1. In a circular knitting-machine, the combination with a revoluble needle-cylinder, of a sinker-carrying ring secured to and revoluble with said cylinder, a frictionally mounted normally non-revoluble sinker-cam-ring supported by said sinker-ring, a manually controlled pivoted latch-guard normally encircling the upper portion of the needles, and peripherally spaced stops secured to said cam-ring and normally engageable with the latch-guard for controlling the short angular movements of the cap-ring during the production of normal circular and reciprocatory knitting, arranged whereby upon elevating the latch-guard the latter is automatically disengaged from said stops, the knitting threads rendered inactive and the cam-ring is carried around in unison with the needle-cylinder, as in transferring, thereby temporarily preventing the sinkers from endwise radial movement.

2. In a circular knitting-machine, the combination with a revoluble needle-cylinder, a stationary post member, and an annular latch-guard pivoted to the post, of a sinker cam-ring mounted for normal vibratory movement in a horizontal plane at the upper end of the needle-cylinder, and laterally spaced stops fixed to the said sinker-ring; said stops being normally engageable with a member of the latch-guard for limiting the vibratory movements of the sinker cam-ring, the latter being adapted to revolve freely in unison with the needle-cylinder when the latch-guard is swung upwardly from the circular path of said stops

3. In a knitting-machine of the general character described, the combination of the revoluble needle-cylinder, a sinker-cam-ring normally mounted for vibratory movement on top of the needle-cylinder, a pivoted latch-guard, and means constituting stops, carried by the cam-ring and engageable with a member of the latch-guard when the latter is in the normally dropped position for limiting the angular vibratory movements of the cam-ring; said stops being adjustable relatively to each other for varying the degree of said angular vibratory movements of the cap-ring, the latter being capable of complete rotation concurrently with the needle-cylinder upon swinging the latch-guard upwardly from its normal position to disengage it from said stops.

4. In a circular knitting-machine pro-

- vided with a revoluble needle-cylinder, a 5
sinker-ring secured to the cylinder and a
sinker-cam-ring frictionally supported there-
on, the combination therewith of a bracket
member fixed to the cam-ring, said bracket
member having a pair of horizontally ar-
ranged stops alining with each other ad-
justably mounted thereon, means for hold-
ing the stops in such adjusted positions, and
10 a manually controlled relatively stationary
pivoted latch-guard normally positioned
above the needle-cylinder, said guard hav-
ing a member engageable with said stops for
limiting the angular movements of the cam-
ring, arranged whereby upon swinging the
15 latch-guard upward out of the circular path
of the stops the cylinder and cam-ring are
adapted to revolve bodily in unison so as to
temporarily prevent endwise movements of
20 the sinkers in the said sinker and cap-rings
for the purpose set forth.
5. In a knitting machine, the combina-
tion, with a revoluble needle-cylinder, of a
sinker-ring revoluble with said cylinder, a
25 sinker-cam-ring frictionally mounted on
- said sinker-ring, and means for normally
holding said sinker-cam-ring from rotating
with said needle-cylinder, said holding
means being adapted to be released to per-
mit said sinker-cam-ring to rotate with said 30
cylinder.
6. In a knitting machine, the combina-
tion, with a revoluble needle-cylinder, of a
sinker - ring revoluble with said cylinder, a
sinker - cam - ring frictionally mounted on 35
said sinker-ring, a pivoted latch-guard, a
stop carried by said sinker-cam-ring and
adapted to engage said latch-guard in its
normal position to normally hold said
sinker - cam - ring from rotating with said 40
needle-cylinder, whereby, when said latch-
guard is raised, said sinker-cam-ring will be
free to rotate with said cylinder.

In testimony whereof I have affixed my
signature in presence of two witnesses.
